STITCH-FORMING MECHANISM

John Kozibroda, Hamtramck, Mich.

Application December 5, 1938, Serial No. 243,983

3 Claims. (Cl. 112—98)

This invention relates to stitch-forming mechanism, and its principal object is to provide a mechanism of the character referred to which is adapted to produce upon a fabric a series of "cross stitches," that is to say, stitches in the form of an **X** which are arranged in straight lines or in other geometric forms to produce ornamental patterns upon articles of clothing. Such stitches form the basis of many popular designs, particularly in Scandinavian and other European countries, and are also used to a considerable extent in the United States.

Machines at present employed for the purpose recited are generally of the type known as chain stitch machines, and with such machines the only way to make a series of cross stitches, arranged in a straight line for example, is to make a series of zigzag stitches through the full length of the design and then to reverse the work and make a like series at right angles to the first. Similarly, when forming a design having therein different colors, a series of chain stitches must be first formed in one color and then the design must be gone over with threads of succeeding color until completed. In both of these cases it is obvious that, due to the difficulty of laying the additional rows of stitches accurately in relation to the first rows, the work must be first stamped or marked upon the fabric so that the design can be followed correctly by these successive operations.

A further objection to the use of chain stitch machines for the purpose set forth is due to the fact that if the lock in a single stitch becomes loose or pulls out, the whole row of stitches is destroyed. In order to overcome this defect, various attempts have been made to construct a lock stitch mechanism for producing the elements of the cross stitch, but such mechanisms have the inherent difficulty that the completion of one bar or element of the stitch leaves a thread which extends from the upper surface of the fabric to the needle, so that when the work is completed there are a number of excessive threads lying upon the said surface which must be removed by manual means.

In order to produce a cross stitch design in various colors, machines have been constructed with a plurality of needle bars, one for each color, arranged to form a series of chain stitches, but this method has the disadvantage that a number of ends of thread are left upon the face of the fabric, and these become mixed together and require considerable work after the actual stitching has been completed.

According to the present invention I have provided a stitch-forming mechanism by which a single element or bar of a cross stitch may be completed upon the fabric in lock stitch form without leaving any loose ends and without any threads remaining between the fabric and the needle. In other words, the thread is entirely released from the needle after the completion of each stitch and is retained upon the bobbin only ready for the next stitch, so that the bars or elements may be applied one after the other in any desired pattern or sequence, either zigzag or straight line, as well as in the form of embroidered monograms or pictorial designs. Similarly, by my improved mechanism the color of the thread may be changed at any point, so that even a single cross stitch may be made with the intersecting elements or bars of different colors.

A further improvement which resides in cross stitches made by my improved mechanism is due to the fact that, while when such stitches are made by zigzag and other methods above recited each element of the stitch consists of a single thread only so that the pattern produced has a very thin and feeble appearance, each element of the cross stitch produced by my device consists of a double thread which gives it a bold and substantial appearance such as is found in cross stitch work done by hand.

In order that my invention may be readily understood by those skilled in the art to which the same relates, I will now describe a preferred modification of my improved mechanism with reference to the accompanying drawings in which—

Figure 1 is a vertical longitudinal section showing a machine constructed in accordance with my invention.

Figure 2 is a plan view of the same taken in section on line 2—2 of Figure 1.

Figure 3 is a front elevation of the same.

Figure 4 is a vertical section of the same taken on line 4—4 of Figure 1.

Figure 5 is a fragmentary horizontal section of the same taken on line 5—5 of Figure 4.

Figure 6 is a fragmentary vertical elevation taken partly on line 6—6 of Figure 4 and partly on line 61—61 of the same figure.

Figure 7 is a fragmentary section taken on line 7—7 of Figure 8.

Figure 8 is a fragmentary longitudinal vertical section corresponding to Figure 1, but showing the shuttle and mechanisms together with the instrumentalities for operating the same.

Figure 9 is a front view of the shuttle.

Figure 10 is a horizontal section of the same taken on line 10—10 of Figure 8.

Figure 11 is a composite diagram showing the cams for operating the needle bar and also the special hook which forms a part of the needle.

Figure 12 is a front elevation of the last-mentioned cam in an alternative position during its operation.

Figure 13 is a vertical section through my improved needle together with my special hook used in conjunction with the same.

Figure 13A is a fragmentary enlarged view of the same.

Figure 14 is a front elevational diagram showing the respective positions of the shuttle and the needle during one phase of their cycle of operations.

Figure 15 is a diagram showing the same in plan view.

Figure 16 is a diagram similar to Figure 14 showing another phase of the cycle and

Figure 17 is a plan view corresponding thereto.

Figure 18 is a diagram similar to Figure 14 showing another phase of the cycle and

Figure 19 is a corresponding plan view.

Figure 20 shows yet another phase of the cycle and

Figure 21 is a corresponding plan view, and

Figure 22 is a fragmentary section through a portion of the fabric being operated upon showing a single stitch as completed therein, and

Figure 22A is a plan view of the same.

Like characters designate corresponding parts throughout the several views.

The main frame or housing of the machine in the example shown consists of a vertical member 1, an upper horizontal member 1A and a lower horizontal member 1B, the three portions being preferably cast in one piece though this is not essential. In bearings in the rear wall of the member 1 and in the front wall of the same designated 2 is the main driving shaft 3 operated from the motor 4 through pinion 41 and gear 42. Within the member 1A and parallel to the shaft 3 is a shaft 5 driven through chain 51 and sprockets 52, 53 from the shaft 3 and carried in bearings 54, 55 as shown clearly in Figure 1. Upon the front portion of the member 1A is a housing 1C in which is slidably supported the hollow vertical needle bar 6 having a cam roller 61 which engages a groove in the cam 62 by which vertical reciprocation of the needle bar is obtained in the manner well known in the art. Within the lower end of the needle bar is secured a needle 63 which consists essentially of a tubular member having a notched pointed end as shown in Figure 13A and within this tubular member is a member 7 having at its lower end a complementary hook or barb 71 and having its upper end threaded or otherwise secured within a rod 72, the said rod being slidably mounted within the needle bar 6 and having at its upper end a head 73 with which engages the outer arm 74 of a rocking lever, the other end 75 being connected to a rod 76, the lower end of which is of bifurcated shape as indicated at 77 and carries a roller 78 arranged in co-operative relation with a cam 79 upon the shaft 3. By this arrangement the needle bar 6 and the rod 72 are operated in timed relation from the driving shaft 3 in a manner and for purposes to be hereinafter explained. The rocking lever 74, 75 is mounted upon a pivot 75A carried in a bracket 75B upon the member 1A.

Upon the upper surface of the member 1B is

a trackway 1D upon which travels a frame 8 provided with rollers 81 having flanges adapted to engage the said trackway. The frame 8 is provided with a pair of trackways 82 on which a frame 9 is arranged to travel upon rollers 91 pivoted at 92 to lugs upon the said frame. The frame 9 carries at its rear end a pair of vertical members 93 which terminate in horizontal arms 94 and in these arms is journaled a shaft 95 which carries a hollow roller 96 adapted to receive a roll of fabric 10 to be operated upon by my improved mechanism. The fabric 10 passes diagonally as indicated at 101 to a roller 102 mounted upon a shaft 103 which is supported in journals in the members 93. Thence the fabric extends horizontally as indicated at 104 over an idler roller 105 to a roller 106 mounted on a shaft 107 in the front portion of the frame 9. The shaft 95, as shown in Figure 3, is provided with a casing 97 within which is a coil spring 98 adapted to maintain the fabric tight under all conditions, and upon the shaft 103 is a ratchet wheel 108 operated by a pawl 109 and actuated by a mechanism to be hereinafter described so as to feed the fabric forward at predetermined intervals, to receive the successive rows of cross stitches, in the direction of the arrow y in Figure 1.

The raw fabric 10, as will be seen by reference to Figure 1 of the drawings is fed from the roller 106, under the needle, around the roller 102 and thence to the roller 96 which receives the finished material as indicated by the arrows x, y. In order to maintain a proper tension upon the fabric there is provided upon the shaft 107 a frictional tension device, designated 107' in Figure 3, which device may be of any conventional form adapted to resist feeding of the material under the action of the pawl 109 and ratchet wheel 108 as will be understood.

Movement of the pawl 109, for feeding material through the machine, is effected through a rod 13, lever 131, rod 132 and manually operated key lever 133, the lever 131 being moved in a downward direction against the action of a spring 134 by means of rods 132, 132' and key lever 133, the said lever being held in the upward limit of its movement by means of a stop pin 135. In order that the rod 132 may be operated effectively in any position during the lateral travel of the frame 9, there is provided a transverse shaft 134' carried on links 135' pivoted at 136 to brackets 137 upon the member 1B. The rod 132' is provided with an eye or loop which engages the shaft 134' during any position of its lateral travel so that the feeding mechanism can be operated at any position of the frame 9.

Travel of the frame 8, longitudinally of the machine, is effected through two pinions 11, keyed upon a stationary shaft 110, which engage racks 83 cut in the upper surfaces of the side members 84 of the frame. The shaft 110 is supported in bearings upon the main frame members 1B and is rotated in alternate directions, so as to move the frame 8 forwardly or rearwardly respectively, of the machine, by means of ratchet wheels 111, 112, the wheel 111 being rotated one tooth at a time by the pawl 113, rod 114 and manually operated key-lever 115, while the wheel 112 is similarly rotated in the opposite direction by the pawl 116, rod 117 and key lever 118.

Travel of the frame 9, transversely of the machine, is effected through two pinions 12, keyed upon a shaft 120, which engages racks 85 carried upon the frame 8 and positioned immediate-

ly over the rollers 91. The shaft 120 is supported in bearings 120' in the frame 9 and is rotated in alternate directions, so as to move the said frame towards one side or the other of the machine, by means of ratchet wheels 121, 122, the wheel 121 being rotated one tooth at a time by the pawl 123, rod 124 and manually operated key-lever 125, while the wheel 122 is similarly rotated by the pawl 126, rod 127 and key-lever 128. The wheels 121, 122 are keyed upon the shaft 120 and held against endwise movement by collars 129.

It will be understood from the foregoing description that, by operating the appropriate key-levers, the frame 9, carrying the fabric and fabric feeding mechanism, may be moved back and forth in alternative directions relative to the needle 63, and it will be obvious that by simultaneously moving the frame one step in a forward or rearward direction and one step laterally a diagonal stitch may be applied to the fabric so as to form one element of the cross-stitch which my machine is primarily designed to produce.

14 is the needle plate having the usual opening 141 through which the needle 63 operates, and beneath this plate is a block 142, supported upon transverse guide rods 143, in which are mounted a series of shafts 15 each carrying a rotary hook of conventional type 151 having therewithin a bobbin case 152 and enclosed bobbin 153 by which is formed a lock stitch in a manner to be herein-after described. Each of the hooks 151 is adapted to carry in its bobbin case a thread of a different color, and means are provided for moving the block 142 laterally so as to bring either of the hooks 151 into alignment with the needle 63.

Each of the shafts 15 has upon its inner end a collar 154 having a notch adapted to engage a driving member 155 upon the end of the shaft 3 so that the shafts 15 may be brought selectively into driving relation with the shaft 3 by sliding the block 142 laterally upon its guide rods. Secured to the needle plate 14 and extending downwardly therefrom is a stud 156 carrying at its lower end a bearing 157 for the shaft 3, and intermediate this bearing and the needle plate is a bevel gear 158 to which is rotatably secured a cam 159, and meshing with the gear 158 is a pinion 160 pinned to the shaft 3. The gear 158 is twice the pitch diameter of the pinion 160 so that the cam 159 rotates at half the speed of the co-acting hook 151 for a purpose to be hereinafter explained. The general arrangement of the parts just described is shown more clearly in Figures 7, 8, 9 and 10, which are drawn to an enlarged scale.

In co-operative relation with the cam 159 is a rod 161 guided in a bearing 162 upon the under-side of the needle plate and having a rounded end 163 which is kept in contact with the cam by means of a helical spring 164. Upon the front end of the rod 161 is carried a pin 165 which engages in a slot 170 in a swinging lever 17 pivoted at 171 to the needle plate. The lever 17 has integral with it a geared segment 172, the teeth of which mesh with a pinion 173 rotatably mounted upon a stud 174 and fixed to a lever 175, the free end of which carries an arcuate looper 176 having at its outer end a notch 177. Thus, rotation of the bevel gear 158 together with the cam 159 causes reciprocation of the rod 161 and a to and fro movement of the lever 17, which latter movement produces a circular reciprocation of the looper 176.

It should be here noted that connection of the gear 42, driven from the motor 4 through a pinion 41, is effected through a clutch 42A operated by a bell-crank lever 42B, vertical rod 42C, and key-lever 42D, the said clutch being one of the many well known conventional types by which one rotation only of the shaft 3 is produced by downward pressure on the key-lever, after which rotation the said clutch is automatically disengaged. This form of clutch is so well known in the art that it is not deemed necessary to further describe it.

It will be noted further by reference to Figures 11 and 12 of the drawings that a differential movement is established between the needle 63 and the hook 71. In these figures are shown diagrammatically the cam 62 which operates the needle 63 and the cam 79 which operates the hook 71, the cam 62 being shown diagrammatically in broken lines in Figure 11. Comparison of the two cams shows that the cam 79, while following for the most part of its revolution the general shape and timing of the cam 62, has at one point a raised portion 79' which is so arranged that at a certain point in the cycle of operations the hook 71 is moved downwardly away from the co-acting end of the needle 63. In other words, the needle and the hook are in contact with one another, as shown in the large view Figure 13A, so as to engage a thread, but the said thread is released at such time as the projection 79' comes in contact with its co-acting roller 78, producing a gap between the hook and the needle so as to release the thread.

35 I will now describe the formation of a single stitch by my improved mechanism with particular reference to Figures 14 to 22 of the drawings, in which the parts are shown to an enlarged scale. Assuming that a stitch has just been completed as indicated at W in Figure 14, the free end of the thread connected thereto extends downwardly into the bobbin case as indicated at a, and at this point the needle 63 reaches its downward position with the hook spaced therefrom so as to receive a thread. At this point the looper 176 arrives at the position indicated in Figure 15, carrying the thread a into the space between the hook and the needle as shown. The hook now rises into contact with the needle 63, holding the thread a loosely and drawing it upwards into the position shown in Figure 16. We have now a bight of the thread held in the hook, the two portions of the said bight being designated a and b, (the looper 176 in the meantime has been returned to its resting or inoperative position as shown in Figure 17), the needle now descends with the hook in the closed position as shown in Figure 18, carrying with it the threads a and b which then present an open loop. Through this loop the hook 151 now passes, pulling down the threads a and b and causing the bobbin case with its bobbin and thread to pass through the bight so as to form a lock-stitch, which, as it gradually becomes tightened in the fabric, presents the formation indicated in Figures 22 and 22A. The looper 176 meantime has been retained in the inoperative position as indicated in Figures 19 and 21, which latter correspond to Figures 18 and 20, respectively, the said looper remaining in this position until the parts again resume the relative positions shown in Figure 14, when another cycle is commenced.

In the manner just described we have formed a single element of a cross stitch which will occupy a diagonal position upon the fabric as indi-

cated at S' in the fragmentary plan view, Figure 22, and it will be obvious that by proper manipulation of the keys, another stitch, as indicated at S2, may be laid upon the fabric at right angles to the first stitch. In this manner any number of cross stitches may be applied to the fabric in successive rows throughout its length or in single rows or multiple rows at any desired spacing along the said length.

The formation of my improved cross stitch has so far been described only as applied to a single color of thread. I will now describe further the method of producing stitches of various colors in any desired arrangement upon the fabric. For this purpose, the block 42 above referred to slidably supported upon the guide rods 143, is provided with a transverse notch 144, as shown more clearly in Figures 4 and 5, and in co-operative relation with this notch is a series of stop levers 145, one for each of the hooks 151, these stop levers being of different lengths as indicated at 145', 145'', 145''', and 145'''', each of the stop levers being provided with a corresponding groove in the block 142, the arrangement being such that each of the levers is raised up into its corresponding groove when selectively operated in a manner to be now described.

The levers 145 are pivoted at 146 to a fixed member, and the outer end of each lever projects beyond the frame, as indicated at 147, so as to lie in the path of one or the other of a series of vertically slidable rods 148 having at their upper ends the keys 148' and being guided in lugs 86 upon the supporting frame. Each of the rods 148 has pivoted to it a pulley 149 carried upon a pin 149', the said pulley being adapted to engage the bight of a cord 149'' which passes over an idler pulley 149''' and is anchored to the end of a sliding bar 180, the said bar being slidably mounted in dove-tailed grooves in a block 181 and having at its free end a dog 182 which is adapted to engage the block 142 when it is moved to the left hand in Figure 4 by depressing its corresponding key 148'. It will be observed that the keys 148' are of different initial heights upon the frame so that by pressing either down to the limit of its travel, its corresponding cord 149'' is shortened sufficiently to draw the block 142 forward to a sufficient distance to bring one of the rotary hooks 151 together with its driving shaft 3. In this manner the rotary hooks 151, shown in the drawing as four in number, and each carrying upon its bobbin a thread of a specific color, may be brought into cooperative relation with the needle 63 since, as will be understood, the pressing of one of the keys 148' will cause the block 142 to be moved forward to the required distance and at the same time will operate the corresponding locking lever 145 so as to engage the common notch 144 in the block. After one of the keys has been depressed, as will be described, a pawl 87 will engage a notch 148'' in the rod 148 and retain the same in the depressed position. When the stitch of the predetermined color has been completed, the pawl 87 is released by pressing the tail 88 upon it, and the block 142 is returned to its initial position as shown in Figure 4 by means of the spring 144' and at the same time the push rod 180 is also returned to its initial position by means of the spring 183. It will, of course, be understood that either one of the rotary hooks may be held in operative position while forming two or more stitches as de-

sired so as to produce the desired pattern upon the fabric.

It will be understood that moving of the rotary hooks together with their bobbin cases and contained bobbins back and forth would ordinarily result in a slack condition of the several threads, and in order to prevent this I provide upon each of the bobbins 153 a projecting shaft 153' the outer end of which is supported in a bearing in the conventional bobbin retainer 153''. Upon each of the shafts 153' is a pinion 153''' and upon the frame 8 are the upper and lower racks 89, 89' which engage these pinions whenever they are moved in one direction or the other as will be understood from Figure 4, the arrangement being such that when the hooks are moved to the left hand direction in Figure 4 the pinions engage the racks 89' and wind up the thread on the bobbins, whereas when the hooks are traversed in the right hand direction in Figure 4 the pinions engage the upper rack 91 and thread is payed out. In this manner the several threads are retained in an orderly and properly tensioned condition so as to make certain the picking up of either of the threads in the bobbin at the proper time in the manner above described.

Means, not shown, are provided for ensuring that the groove in the clutch collar 154 remains in a horizontal position at all times when the shaft 15 is stationary, so as to facilitate its proper engagement with the tongue upon the driving member 155. It will be noted also that the clutch 42A is so arranged as to rotate the shaft 3 through two revolutions each time it is put into engagement for reasons which will be readily understood.

It will be observed from the foregoing description and by reference to the drawings that I have provided an improved mechanism which is 40 eminently adapted for the purposes above recited, and while I have herein described and shown a preferred embodiment of my invention, it will be readily understood by those skilled in the art to which the same pertains that various modifications 45 in detail may be made to meet any particular or peculiar requirements without departing from the spirit of my invention as defined in the appended claims.

Having thus described my said invention, what 50 I claim and desire to secure by Letters Patent of the United States is:

1. In a stitch-forming mechanism, the combination, with a tubular member, of a hook element slidably mounted within said member and 55 adapted to reciprocate therewith and also independently thereof, said member having a notch for receiving the hook of said element, whereby said member supports the hook element and also acts as a latch for retaining the thread therein.

2. In a stitch-forming mechanism, the combination, with a vertically reciprocating needle, of a horizontal shuttle-driving shaft, a series of 60 shafts each carrying a hook shuttle and adapted to be selectively brought into driving relation with

65 said first-mentioned shaft, whereby stitches of various colors may be formed, and means for positioning said driving shafts comprising a carrier element having bearings for all of said shafts, manually operated means for moving said element, locking means for holding said element temporarily in a given position, and means for returning said element to initial position when said locking means is rendered inoperative.

3. In a stitch-forming mechanism having a 70 single needle and a series of aligned rotary hook

shuttles adapted to be brought selectively into co-operative relation with said needle, each of said shuttles having therein a bobbin containing thread, means for maintaining a constant tension in the respective threads regardless of the travel of said shuttles back and forth, said means comprising a pinion upon each bobbin, and a

pair of racks engaging said pinions at upper and lower diametrically opposed points, whereby lateral travel of the shuttles will cause rotation of said bobbins to wind or unwind the threads thereon as required.

JOHN KOZIBRODA.
